UNITED STATES PATENT OFFICE.

WILLIAM V. ROBINSON, OF OWOSSO, MICHIGAN, ASSIGNOR TO THE INDEPENDENT STOVE COMPANY, OF OWOSSO, MICHIGAN, A CORPORATION OF MICHIGAN.

COMBINATION GAS AND COAL RANGE.

Application filed May 16, 1921. Serial No. 470,133.

To all whom it may concern:

Be it known that I, WILLIAM V. ROBINSON, a citizen of the United States of America, residing at Owosso, in the county of Shiawassee and State of Michigan, have invented 5 certain new and useful Improvements in Combination Gas and Coal Ranges, of which the following is a specification, reference being had therein to the accompanying drawings.

The invention relates to combination coal and gas stoves and consists in the novel construction as hereinafter set forth.

In the drawings:

15 Figure 1 is a perspective view of the range looking from the rear side;

Figure 2 is a horizontal section thereof;

Figure 3 is an enlarged horizontal section;

20 Figure 4 is a perspective view of the burner;

Figure 5 is a rear elevation; and

Figure 6 is a vertical section.

A is a coal range of any suitable construction, B is the oven thereof. C is a gas burner 25 which is formed at the inner end of the tubular arm D passing outward through a slot E in the end wall of the oven adjacent to the bottom thereof. The outer end of the arm D is provided with a hub portion F 30 which is pivotally secured in bearings to permit of swinging the arm D completely in the slot E. G is a gas-mixing chamber formed in a stationary hollow casting adjacent to the hub F and said hub is formed with 35 a portion F', forming a valve or shutter for closing off said mixing chamber when the arm D is within the slot E. When, however, the arm is swung inward into the oven, a port F² will be registered with the chamber

40 G, establishing communication between said chamber and the hollow arm. H is a gas supplied valve having a nozzle H' discharging into the mixing chamber G. I is a rock shaft for operating the valve H, which shaft

45 extends to the front of the range and is provided with a crank handle J. The rock shaft I has an upwardly-extending rock arm K with the pin K' thereon engaging a slotted bearing in a rock arm L. This rock 50 arm is connected by a link M and bell crank lever N to a rod O, which extends into the rear flue P and operates a valve Q covering a vent V from the oven into said flue. There is also a link R connecting the rock

shaft I with a bell crank lever S and rod T 55 leading to a slide valve U for opening and closing an air vent through the bottom of the stove. Thus whenever the rock arm I is turned into a position to open the gas valve, it will also open the vent V, admitting 60 air into the oven in the center of the annular burner C and will operate the valve Q to open the vent into the exhaust flue. This will furnish air for combustion to the burner and escape for the gaseous products of combustion. On the other hand, when the rock arm I is turned to close the gas valve, it will simultaneously close the air vent V and chamber Q.

In order to insure the turning off of the 70 gas when the burner and arm D are swung outward into the slot E, there is arranged upon the hub F a projecting lug W. This engages a rod X which is pivoted to the arm K' and the arrangement is such that when 75 the arm D is swung into the slot E, the lug W will actuate the rod X so as to rock the arm K and close the valve H. The parts will also function to swing the arm D inward into the oven whenever the rock shaft 80 I is turned to open the valve H. Thus there is no danger of leaving the gas on when the rock arm is out of operative position, and also when the rock arm is located within the slot E, the flange F' will absolutely cut 85 off communication between the mixing chamber and the hollow arm.

A stove constructed as described can be used either with solid fuel or with gas and can be quickly adjusted for the use of either 90 fuel. When the arm D is swung outward into the slot E, it completely removes the burner from the oven chamber and also forms a closure for the slot E thus providing 95 to a certain degree the accumulation of dirt on said burner and in the slot.

What I claim as my invention is:

1. A combination gas and coal range comprising an oven having a slotted side wall, 100 a gas burner having a hollow arm pivotally mounted outside of the oven chamber and adapted to be swung inward or outward through said slot, and means for supplying a combustible gaseous mixture to said hollow arm.

2. A combination gas and coal range comprising an oven chamber having a slot in

- one wall thereof adjacent to the oven bottom, a gas burner having a hollow arm pivotally mounted outside of the oven and adapted to be swung inward through said 5 slot, said arm forming, when swung outward, a closure for said slot, and means for supplying a combustible gaseous mixture to said hollow arm when swung inward into the oven.
- 10 3. A combination gas and coal range comprising an oven having a slot in one wall thereof adjacent to the oven bottom, a gas burner having a hollow arm pivotally mounted outside of the oven and adapted 15 to be swung inward through said slot, said arm forming a closure for the slot when swung outward, a gas mixing chamber adjacent to the outer end of said hollow arm and a valve or shutter on said hollow arm 20 for closing off said gas-mixing chamber when said arm is swung outward and for establishing open communication between said arm and mixing chamber when the burner is swung into the oven.
- 25 4. A combination gas and coal range comprising an oven having a slot in one wall thereof adjacent to the oven bottom, a gas burner, a hollow arm integral with said gas burner having its opposite end pivotally 30 mounted outside of said oven, said arm being adapted to be swung through said slot to carry said burner into the center of the oven and to close the slot when swung outward, an air inlet port in the bottom of the 35 oven registering with said burner when in its inner position, means for supplying a combustible gas to said hollow arm, and means operated by the outward swinging of said arm for closing said air inlet port.
- 40 5. A combination gas and coal range comprising an oven having a slot in one wall thereof adjacent to the bottom, an annular gas burner provided with a hollow arm, said arm being pivotally mounted outside of 45 said oven and being adapted to be swung inward through said slot into the center of the oven, an air inlet port for registering with the center of said burner when in its inner position, a valve or shutter for closing 50 said port, and means operated by the swinging of said hollow arm outward or inward for actuating said valve to respectively close and open said air inlet port.
6. A combination gas and coal range comprising an oven having a slot in one wall 55 thereof adjacent to the oven bottom, an annular burner having a hollow arm pivotally mounted outside of said oven and adapted to be swung inward through said slot, a port in the oven bottom in registration with the center of said burner when in its inner position, a valve for closing said port, an outlet vent in said oven, a shutter for closing said vent, and means operated by the swinging of said arm outward or inward for 60 operating said valve and shutter to open the same when the burner is in the oven and to close the port when the burner is swung outward.
7. A combination gas and coal range 70 comprising an oven having a slot in the side wall thereof adjacent to the bottom, a burner having a hollow arm pivoted outside of said oven and adapted to be swung inward through said slot, a gas supplied 75 valve for said hollow arm, means for opening and closing said gas supplied valve, and means operated by the outward swinging of said hollow arm for automatically closing said gas supplied valve. 80
8. In a coal and gas range, the combination with an oven, of a gas burner rockably mounted outside and adjacent thereto and adapted to move into and out of said oven, means for rocking said burner and means 85 cooperating with said rocking means for automatically controlling the gas supply to said burner.
9. In a coal and gas range, the combination with an oven adapted to receive a movable gas burner, a movable gas burner pivotally mounted outside and adjacent thereto, means for moving said burner into and out of said oven, means for automatically supplying a combustible gaseous mixture to 90 said burner when the same is moved into said oven and for cutting off said supply when the burner is withdrawn from the oven. 95
- In testimony whereof I affix my signature.
- WILLIAM V. ROBINSON.
